UNITED STATES PATENT OFFICE.

JOHN T. APGAR, OF NEW YORK, N. Y.

ARTIFICIAL LEG.

No. 842,609.

Specification of Letters Patent.

Patented Jan. 29, 1907.

Application filed September 8, 1906. Serial No. 333,768.

To all whom it may concern:

Be it known that I, JOHN T. APGAR, a citizen of the United States, residing at New York city, borough of Manhattan, county 5 and State of New York, have invented certain new and useful Improvements in Artificial Legs, of which the following is a clear, full, and exact description.

This invention relates to artificial legs, and 10 has for its object to provide a simple, cheap, and efficient adjusting means by which the tension or friction of the upper end of the socket member of the artificial leg may be regulated in order to firmly hold the stump 15 of a leg therein. As these sockets are usually made of leather, climatic changes or the moisture of the body causes the leather to swell or otherwise affect the same, and my invention is intended to adjust the socket 20 member to suit the conditions.

To these and other ends, which will herein-after appear, my invention comprises the novel features of improvement and combination and arrangement of parts, which I will 25 now proceed to describe and finally claim, reference being had to the accompanying drawings, forming part hereof, wherein—

Figure 1 illustrates a perspective rear view of a portion of a leg or a stump to which 30 the socket member of an artificial leg is applied having my improved adjusting device attached. Fig. 2 is a cross-sectional plan view thereof, the section being taken on a line *a a* in Fig. 1. Fig. 3 is an enlarged rear 35 elevation of the adjustable region of the socket member and showing a modified form of adjusting means in which a right and left hand threaded screw is used. Fig. 4 is a cross-sectional plan view thereof, the section being taken on a line *b b* in Fig. 3; and Fig. 5 is an enlarged perspective view of a 40 modified form of adjusting means in which a swivel-screw and wing-nut are used.

Like reference characters are intended to 45 indicate corresponding parts in the several views.

Referring to the accompanying drawings, the numeral 4 indicates the upper or socket member of an artificial leg, while 5 indicates 50 a leg-stump held thereby. As it is impracticable to foretell the requisite amount of tension required to hold the stump firmly within the socket member, it is necessary to provide an adjustable device by which the said tension 55 can be regulated to suit conditions. For instance, if the weather be damp the leather

will swell, which may also happen by reason of moisture emanating from the leg-stump, thus causing the socket member to loosen, in which case the upper end of the socket member embodying my improvement can readily be tightened, and, on the other hand, when the leather dries out it can easily be loosened, as may be desired. In order to effect such adjustability, the rear or other portion of the 60 socket member is vertically slotted, as at 6, Fig. 1, and at about the corners 7 and 8 I preferably rivet angle-brackets 9 and 10 and through the members 11 and 12 thereof I pass a threaded adjusting-screw 13. By referring to Fig. 2 it will be seen that the said screw engages a threaded opening in the member 11 of the bracket 9, but passes freely through the member 12 of the bracket 10. The screw 13 is provided with a slotted head 75 14, into which a screw-driver or other means can be inserted in order to turn the screw 13, whereby the corners 7 and 8 of the socket member can be drawn together or loosened for the purposes hereinbefore mentioned. 80

In the modified form shown in Figs. 3 and 4 the openings in the members 11 and 12 of the brackets 9 and 10 are threaded oppositely or right and left handed. To doubly secure the said brackets and to increase their 85 resistance to lateral displacement, I provide upon each bracket a prong or pointed flange 15, which can be embedded in the material, as shown. In order to draw the corners 7 and 8 together or force them apart, a right 90 and left hand threaded adjusting-screw 16 is provided, the same carrying a thumb-wheel 17. It will be understood that the said screw engages the correspondingly-threaded openings of the said brackets 9 and 10. By 95 turning the wheel 17 the said socket member can be adjusted at will. The presence of the thumb-wheel 17 obviates the necessity of employing a screw-driver for rotating the screw. 100

In the form of my invention shown in Fig. 5 somewhat different brackets are used, the bracket 18 being provided with a jaw 19, into which the eye 19' of an adjusting-screw 20 is loosely fitted and held by a pin 21, the 1c other bracket 21' being slotted, as at 22. The screw 20 is threaded, as shown, and carries a wing-nut 23. By manipulating the said wing-nut the corners 7 and 8 can be drawn together or allowed to spring away 110 from each other in obvious manner. When it is desired to entirely withdraw the socket

member from the leg-stump, the screw 20 can be swung outwardly and away from the bracket 21'.

By having the regulating or adjusting device attached to the socket member any chances of loss or neglect in applying are obviated, and by my improved construction less weight is added to the leg than if the said adjusting device was a band or the like.

Having now described my invention, what I claim, and desire to secure by Letters Patent, is—

1. An artificial leg having a vertical slot at the upper end of the socket member, said socket member being provided with brackets adjacent to said slot, one of said brackets having an adjusting device pivotally connected thereto, the other of said brackets being adapted to engage said adjusting device 20 and means carried by said adjusting device whereby the tension of said socket member can be adjusted.

2. An artificial leg having a vertical slot at the upper end of the socket member, said

socket member being provided with brackets 25 adjacent to said slot, an adjusting-screw pivotally connected to one of the said brackets, the other of said brackets being adapted to engage said adjusting-screw, and a nut carried by said adjusting-screw adapted to regulate the tension of said socket member.

3. An artificial leg having a vertical slot at the upper end of the socket member, said socket member being provided with brackets adjacent to said slot, an adjusting-screw pivotally connected to one of the said brackets, the other of said brackets being provided with a slot adapted to receive the said adjusting-screw, said adjusting-screw being provided with a nut adapted to regulate the 35 tension of said socket member.

Signed at New York, N. Y., this 6th day of September, 1906.

JOHN T. APGAR.
